(57) **CLAIM**

The ornamental design for a perfume bottle, as shown and described.

DESCRIPTION

FIG. 1 is a front, right-side, top perspective view of a perfume bottle, showing the new design, in a closed configuration;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front elevational view thereof, in an open configuration.

The evenly-spaced broken lines depict parts of the perfume bottle that form no part of the claimed design. The dot-dash lines represent the boundaries of the claim and form no part of the claimed design.

1 Claim, 7 Drawing Sheets
